(57) **CLAIM**

The ornamental design for a safety harness, as shown and described.

DESCRIPTION

FIG. 1 is perspective view from the front of the safety harness of my new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a side elevational view thereof.

FIG. 7 is an opposite side elevational view thereof; and,
FIG. 8 is a side elevational view thereof, showing a rider
wearing the safety harness of my new design.

The motorcycle, rider and passenger shown in broken lines in
FIG. 8, are environmental figures and are not part of my new
design.
